WHEELER & WILSON MANUFACTURING COMPANY, OF BRIDGEPORT,
CONNECTICUT, A CORPORATION OF CONNECTICUT.

BOBBIN-CASE FOR SEWING-MACHINES.

No. 814,341.

Specification of Letters Patent.

Patented March 6, 1906.

Application filed May 10, 1905. Serial No. 259,689.

To all whom it may concern:

Be it known that I, WILLIAM R. ABERCROMBIE, a citizen of the United States, residing at Bridgeport, in the county of Fairfield and State of Connecticut, have invented a certain new and useful Improvement in Bobbin-Cases for Sewing-Machines, of which the following is a full, clear, and exact description.

The object of this invention is to provide a bobbin-case with means for readily applying it to and removing it from its holder, such as the loop-taker or hook of a sewing-machine and for locking the case in the said holder, loop-taker, or hook for use in sewing.

The invention consists, essentially, of a bobbin-case having a central hub, so that it may be applied to a pin fixed in the holder, loop-taker, or hook and on which pin the bobbin is placed, said case having applied to it a pivoted bail, one end of which co-operates with a circumferential groove in the pin, the case being recessed to receive the bail and a portion of the recess having an overhanging flange, serving as a cam to draw the locking end of the bail out of engagement with the groove in the pin when the bail is lifted to disconnect the bobbin-case from the loop-taker or hook, all as I will proceed now more particularly to set forth and finally claim.

In the accompanying drawings, illustrating the invention, in the several figures of which like parts are similarly designated, Figure 1 is a plan view of the bobbin-case. Fig. 2 is a plan view with the top partly broken away and showing the bobbin-case applied to a rotary loop-taker or hook. Fig. 3 is a side elevation with the wire-bail lifted or in the unlocked position. Fig. 4 is a cross-section of the rotary hook and bobbin-case with the parts in locked position, and Fig. 5 is a similar section with the parts in unlocked position.

The rotary loop-taker or hook 1 may be of any approved construction and has rising substantially from its center a pin 2, provided with a circumferential groove 3. This pin 2 receives the usual bobbin or spool 4.

5 is the bobbin-case of usual construction, excepting as I will now proceed to describe. The top of this case is recessed at 6, and the ends of the recess are grooved at 7 and 8. The groove 8 forms an overhanging flange 9. The bail 10, preferably of spring-wire, has a

short end 11, pivoted in a transverse hole 12 in the top of the case and also has a long end 13, which extends through a hole 14 in the top of the case, which hole 14 opens into the hub 15 of the case. By means of this hub the case is mounted upon the pin 2, as shown in Figs. 4 and 5. As shown in Figs. 1, 2, and 4, when the bail is down flat upon the top of the bobbin-case and within its recess 6, the long end 13, herein referred to as the "locking" end, projects into the circumferential groove 3 and locks the bobbin-case to the pin. The ends of the said bail-spring into the grooves 7 and 8, and thereby and by means of the overhanging flange 9 the bail is held in this locked position. When it is desired to unlock the bobbin-case and remove it from the rotary loop-taker or hook, the bail is lifted, as in Figs. 3 and 5, and in elevating it the overhanging flange 9 serves as a sort of cam over which the bail must ride and be spread out, so as to withdraw its locking end 13 from the groove 3 in the pin 2.

Obviously the bail in its elevated position, Figs. 3 and 5, serves as a convenient means for putting on and lifting off and otherwise handling the bobbin-case.

16 is the bobbin tension-spring, and 17 is the bobbin-case stop.

The invention obviously is not limited to a rotary hook or loop-taker as the receptacle for the bobbin-case, since the invention is applicable to other forms of holders for the bobbins, wherein a circumferentially-grooved pin is employed as the bobbin and bobbin-case support.

What I claim is—

1. A bobbin-case having a hub adapted to engage a circumferentially-grooved pin, having a spring-bail pivoted to it, one of the pivot ends or the said bail extending through the bobbin-case into its hub and adapted to engage with the groove in the pin to lock the bobbin-case on said pin.

2. A bobbin-case, having a hub, and a recess in its top terminating in grooves, the said case provided with transverse holes to receive the ends of the bail, and one of said holes extending from center to circumference, and a spring-bail provided with pivot ends, one of which extends through the longer hole into the hub.

3. A bobbin-case, having a hub, and a re-

- cess in its top terminating in grooves, the said case provided with transverse holes to receive the ends of the bail, and one of said holes extending from center to circumference, and a spring-bail provided with pivot ends, one of which extends through the longer hole into the hub, the metal of the case forming a flange overhanging the groove next to the longer end of the bail.
- 10 4. A bobbin-case, having a hub, and a recess in its top terminating in grooves, the said case provided with transverse holes to receive the ends of the bail, and one of said holes extending from center to circumference, and a spring-bail provided with pivot
- 15

ends, one of which extends through the longer hole into the hub, the metal of the case forming a flange overhanging the groove next to the longer end of the bail, the said flange serving to hold the bail in locked position and also serving as a cam to withdraw the locking end of the bail when the bail is elevated.

In testimony whereof I have hereunto set my hand this 9th day of May, A. D. 1905.

WILLIAM R. ABERCROMBIE.

Witnesses:

F. W. OSTROM,

ABBIE M. DONIHEE.

It is hereby certified that in Letters Patent No. 814,341, granted March 6, 1906, upon the application of William R. Abercrombie, of Bridgeport, Connecticut, for an improvement in "Bobbin-Cases for Sewing Machines," errors appear requiring correction, as follows: Line 66, page 1, the hyphen between the words "bail" and "spring" should be stricken out; line 91, after the compound word "bobbin-case" a comma should be inserted, and line 94, the word "or" should read *of*; and that the said Letters Patent should be read with these corrections therein that the same may conform to the record of the case in the Patent Office.

Signed and sealed this 27th day of March, A. D., 1906.

[SEAL.]

F. I. ALLEN,
Commissioner of Patents.
